UNITED STATES PATENT OFFICE.

GEORGE C. SETCHELL, OF NORWICH, CONNECTICUT.

DIE FOR MAKING WOOD TYPE AND METHOD OF PRODUCING THE SAME.

SPECIFICATION forming part of Letters Patent No. 375,008, dated December 20, 1887.

Application filed March 19, 1887. Serial No. 231,482. (No model.)

To all whom it may concern:

Be it known that I, GEORGE C. SETCHELL, a citizen of the United States, residing in the city of Norwich, county of New London, and 5 State of Connecticut, have made certain new and useful Improvements in Dies for Making 10 Wood Type and Methods of Producing the Same, which improvements are fully set forth and described in the following specification, reference being had to the accompanying two sheets of drawings.

My invention is in that class of dies used for impressing desired figures in or on the surfaces of such semi-solid substances as wood, papier-maché, compressed leather, &c., and is especially useful in the production of wood printing-types. I shall therefore describe said invention as applied to such use. Solid steel hand-cut dies have been tried heretofore for this 20 particular purpose with a moderate degree of success; but when the endless variety of styles demanded by the market is considered, the enormous expense to be met has prevented such dies from coming into practical use.

25 My purpose in this present invention is to provide a die which shall embody the strength and sharpness of outline of a solid steel die, but which may be quickly produced without the aid of skilled labor required in the production of such hand-cut dies.

30 To illustrate my invention more clearly I have annexed hereto two sheets of drawings, in which—

Figure 1 is a perspective view of a complete 35 die of my new construction; and Fig. 2, a detached view of the steel center section, which forms an important feature of said die. Fig. 3 is a longitudinal sectional view through the center of the die shown in Fig. 1, and Fig. 4 40 is a cross-section on line xx of the same figure. In Fig. 5 I have shown a variety of untrimmed types, together with the respective steel centers necessary to produce such forms. Fig. 6 45 is a perspective view of one of my die-holders (hereinafter described) having placed in position thereon the steel ribs and center punch which are to form the raised operative portions of the complete die. Said Fig. 6 is intended to explain my method of securing said 50 steel portions when about to pour in the metal

for the supporting-block. Fig. 7 shows the same placed within a flask or mold and ready for the molten metal. Fig. 8 represents a finished type, and Fig. 9 illustrates a simple machine for using dies of my new form to produce type-blanks.

55 My die may be briefly described as a block of type-metal or similar alloy having set therein steel punches conforming in size, shape, and relative positions to the form of type which it is desired to make.

60 I have not, as a rule, found it practicable to press back or "upset" the entire surface of a block at a single operation to leave the complete raised letter; but I have found that it is 65 practicable to both outline the letter by die portions of general rib form and to impress the centers and those acute angular portions which heretofore have been trimmed by hand after the greater portion of the letter has been 70 cut on so-called "pantograph-machines" employed for that purpose.

75 In the production of this new form of die I have called into use such pantograph-machines, and with their help have perfected a simple plan, which I will describe in detail, by means of which I am able to produce metallic impression-dies identical in outline with the patterns from which they are made. 80 Blocks of type-wood, after having received an impression from such dies, may then be placed in the pantograph-machine and the surplus stock around the letter quickly routed off, leaving a perfect type with sharp clean edges, angles, and curves, requiring no hand-finishing.

85 Referring now to the drawings, it will be noted that I have made use of a die for producing a Gothic letter **A** to explain my invention.

90 The reference-letter *a* indicates a steel plate having one edge shaped to conform to that portion of the letter which is to be recessed or pressed back from the printing-surface of the type. These plates *a* vary in shape according 95 to the letter to be made, several different forms being shown in Fig. 5, and are of such height that they project above or beyond the face of the surrounding block of type-metal *b* a sixteenth of an inch, or thereabout. That portion 100

of plate *a* which is inclosed and embraced by the surrounding metal *b* is preferably drilled or cut away, as at *c*, so that said metal may enter and assist in retaining the plate in proper position.

d d represent strips of thin sheet metal corresponding in height with plates *a* and shaped to conform to the outline of the letter. When about to make a die for any particular letter—
10 as, for instance, the **A** here shown—a block of type-wood is placed in a pantograph-machine and a very small cutter is run around the outline and central portions of said letter. These outlined blocks (which I have hereinafter
15 termed my "die-holders") are substantially like the unfinished type-blanks *y* in Fig. 5 when they leave the pantograph-machine.

Within the narrow channel which marks the outline of the letter the strips of sheet-
20 *d* are entered, and within the recessed central portion plate *a* is placed. These steel portions are then pressed firmly down into the said die-holder, (see Fig. 6,) and the device thus formed is inclosed by walls *e*, which are
25 securely clamped about it to form a mold to receive the molten metal. After pouring and cooling the type-metal, the walls *e* are removed and the die-holder pulled off from the face of the metal block, leaving the complete die with
30 steel portions projecting, as in Fig. 1.

It will now be obvious that if the die thus formed is pressed into a block of wood the imprint made by the projecting portions will be identical with that in the die-holder used to support the steel portions in the mold, as above described. The blocks thus impressed (which I term "type-blanks") may then be placed in the same machine which cut the original die-holder and the surplus stock
35 quickly trimmed off, leaving the type, as in Fig. 8, ready for printing.

The letter **A** is a good example of the perfection which may be reached by my new method, as it shows a very acute angle and
40 several approximately square corners in the depressed center, which have heretofore always been trimmed out by hand, so far as I am familiar with the art of wood-type making; but with my new form of impression-dies such
45 angles are as easily made as circles, right lines, or open angles.

Referring to the sectional Figs. 3 and 4, it will be noted that the steel portions which are to perform the punching or impressing extend
50 through the block of type-metal *b*, so that they may find a solid backing in the press, instead of depending entirely on the surrounding type-metal for support. Said type-metal

is only intended as a cheap means for retaining the steel portions in their proper positions and for holding them in the press or machine in which they are used.

In order to establish a system which will dispense with the separate adjustment of the several dies of a font, which otherwise would vary in width, I prefer to make the metal blocks of all the dies of a font of the width of the **W**, or widest letter. The punches and ribs are then located relatively to one edge of the block and occupy more or less of the face of said block, according to the letter. When any die so formed is placed in the press and a piece of type-wood is also placed against a suitable strip or gage on the bed of the press, as in Fig. 9, said wood and die register perfectly without further adjustment.

The several steps necessary to the successful production of a die of my new construction may be summed up as follows: First, a desired type is outlined on ordinary type-wood in a type-cutting machine and the center trimmed out; second, thin ribs bent to proper shape are adjusted in the outline channels and steel punches fitted into the central depressions; third, the device thus formed is placed in a mold and molten metal poured in to support and retain the steel portions; fourth, the wooden die-holder is removed from the die.

Having described my invention, I claim—

1. An impression-die consisting of a rectangular block of fusible metal having located therein and projecting therefrom punches of hard metal (whose impression-faces are in the same plane) and extending through said block flush with its rear face, the projecting portions of said punches conforming in shape, size, and relative position to the centers and outline of the desired letter, all being combined substantially as and for the purpose specified.

2. The within-described method of producing impression-dies of the class referred to, consisting of, first, cutting and outlining a type-block to form a die-holder, as described; second, of forcing into the cut-away portions of said block hard metal punches conforming in size and shape to said cut-away portions; third, of pouring molten metal around the shanks of said punches, and, fourth, of removing the said die-holder.

GEORGE C. SETCHELL.
